Primary Examiner — Derrick Holland*Assistant Examiner* — Lauren Calve(74) *Attorney, Agent, or Firm* — Schroeder Law PC(57) **CLAIM**

The ornamental design for a sizer for garment hanger, as shown and described.

DESCRIPTION

FIG. 1 is a front perspective view of a sizer for garment hanger showing our new design;

FIG. 2 is an enlarged front perspective view thereof according to the broken circle indicated in FIG. 1;

FIG. 3 is an enlarged front elevation view thereof according to the broken circle indicated in FIG. 1, the rear elevation being a mirror image thereof;

FIG. 4 is an enlarged right side elevation view thereof according to the broken circle indicated in FIG. 1, the left side elevation view being a mirror image thereof; and,

FIG. 5 is an enlarged top view thereof according to the broken circle indicated in FIG. 1.

The broken lines shown represent unclaimed subject matter and form no part of the claimed design. The bottom view (not shown) forms no part of the claimed design.

The broken circle shown in FIG. 1 represents the partial enlarged boundary shown in FIGS. 2-5 and forms no part of the claimed design.
